Patented Feb. 15, 1916.

UNITED STATES PATENT OFFICE.

CHARLES D. McARTHUR, OF PITTSBURGH, PENNSYLVANIA, ASSIGNOR TO BLOW STEEL CONSTRUCTION COMPANY, OF HOBOKEN, PENNSYLVANIA, A CORPORATION OF NEW JERSEY.

WALL-MOLD.

1,171,733.

Specification of Letters Patent.

Patented Feb. 15, 1916.

Application filed April 22, 1914. Serial No. 833,618.

To all whom it may concern:

Be it known that I, CHARLES D. McARTHUR, a citizen of the United States, residing at Pittsburgh, in the county of Allegheny and State of Pennsylvania, have invented certain new and useful Improvements in Wall-Molds, of which the following is a specification.

The invention relates to wall molds or forms for use in the formation of concrete walls, which may be at any angle. The objects of the invention are the provision of a cheap, simple, construction which can be very easily assembled and disassembled, and the provision of a light construction having a maximum degree of strength and stiffness in proportion to its weight. One embodiment of the invention is illustrated in the accompanying drawings, wherein—

20 Figure 1 is a front elevation of a wall mold constructed in accordance with my invention, and Fig. 2 is an enlarged section taken through the wall, on the line II—II of Fig. 1.

25 As ordinarily constructed, the mold consists of a series of elongated metal panels A with interposed stiffening and connecting members B. In some cases where panels of less length than the panels A are required to 30 complete a wall, other panels C of wood may be employed, such panels being connected to the members B, however, in the same manner as the panels A, and constituting in effect a modified form of panels.

35 The panels A consist of sheet metal plates 1 provided at their upper and lower edges with the stiffening angles 2, and at their end edges with the angles 3, the angles being secured to the plates by rivets, or in any other 40 desired manner. The end angles 3 having riveted thereto other angle members 4 having laterally projecting flanges 5 provided with upturned lips 6. The angle members 4 are at their inner ends spaced away from the 45 angles 3 to provide the slots 7, the function of which will be explained later. The slots or spaces 7 are secured by the use of spacing members 8, but any other desired means might be employed for securing the necessary slots.

The connecting or stiffening members B

consist of plates 9 provided with outturned flanges 10, thus forming the plates into channel irons. As indicated in Fig. 2, these flanges 10 fit into the slots 7 when the parts 55 are in assembled position, the inner face of the channel at such time being flush with the inner faces of the panels so as to provide an unbroken surface for the concrete.

Intermediate the outturned flanges 10 is 60 a stiffening strip formed by the two sheet metal plates 11 riveted at their inner ends to the channel 9 and having their outer edges outturned to provide the flanges 12. The members 11 constitute a stiffening rib 65 for the channels 9, and in addition coöperate with the locking means hereinafter described. This locking means consists of pins 13 engaging at their inner edges the flanges 5 and at their outer edges extending through 70 perforations 14 in the flanges 12. The pins 13 are provided with slots 14' at their outer ends, and through these slots 14' extend wedges 15 which bear against the inner faces of the flanges 12. When the wedges are 75 pressed or driven firmly into position the pins 13 are cammed inwardly, causing their inner ends to clamp the flanges 5 against the face of the channels 9. The outturned lips 6 upon the flanges 5 serve to position 80 the ends of the locking pins 13 and to hold such ends in position.

The outer edges of the plates 11 are preferably tied together at intervals by means of strips 16 (Fig. 1) preferably perforated as 85 indicated at 17 to permit of the passage of the tie rods to another mold wall placed in opposition to the one illustrated, the channel 9 being of course correspondingly perforated to permit of the passage of the tie 90 rods therethrough. The outturned flanges of the longitudinally extending angles 2 are also preferably perforated as indicated at 18 (Fig. 2), so that the opposing flanges on adjacent panels may be bolted together. 95

In case a panel of odd length is required it may be advantageously built up, the panel C consisting of the boards 17 and the angle members 18 constituting such a built-up structure. Angle members 18 are provided 100 with laterally extending flanges 19 having upturned lips 20, and the functions accom-

plished by these parts are the same as with the angle members 4 heretofore described, the spaces 21 being provided for the reception of the flanges 10 of the channel members 9.

It will be seen that the construction provides an easy and convenient method of assembling and disassembling the panels and stiffeners, the parts being readily separated 10 after the removal of the locking pins 13. Only one style or type of stiffening members is required, and the panels A may be made all of the same size and construction, except in those instances where panels of odd 15 lengths are required, in which case a board panel corresponding to the panel C can be made which will coöperate with the stiffeners and the ordinary locking means. The metal angle members 18 as employed with 20 the board panels may be re-used as often as may be desired with the boards of different lengths. The construction when assembled is exceedingly stiff and strong in proportion to its weight, and may be used for walls of 25 large extent and at varying angles, ranging from the horizontal to the perpendicular. Other advantages incident to the construction will be readily apparent to those skilled in the art.

30 What I claim is:

1. In combination in a wall mold, a channel iron having its flanges projecting outwardly from the wall to be formed and having a longitudinal rib intermediate the flanges projecting in the same direction, a lagging panel on each side of the channel iron with its rear face flush with the rear face of the channel, an angle member secured along the edge of each panel adjacent the channel iron with one flange thereof extending laterally and fitting against the outer face of the web of the channel iron and with the other flange spaced away from the panel thus providing a slot to receive the 45 flange of the channel iron, and coöoperating securing means between the said rib and the lateral flanges of the angle member.

2. In combination in a wall mold, a channel iron having its flanges projecting outwardly from the wall to be formed and having a longitudinal rib intermediate the flanges projecting in the same direction, and having laterally extending flanges at its outer edge, a lagging panel on each side of the channel iron with its rear face flush with the rear face of the channel iron, an angle member secured along the edge of each panel adjacent the channel with one flange thereof extending laterally and fitting 50 against the outer face of the web of the channel iron and with the other flange spaced away from the panel thus providing a slot to receive the flange of the channel, and removable locking pins between the said laterally projecting flanges of the angle member and the flanges of the said rib, the said laterally projecting flanges having outwardly projecting lips adapted to hold the ends of the pins against lateral movement.

3. In combination in a wall mold, a channel iron having its flanges projecting outwardly from the wall to be formed and having a longitudinal rib intermediate the flanges projecting in the same direction, and having laterally extending flanges at its outer edge, a lagging panel on each side of the channel iron with its rear face flush with the rear face of the channel iron, an angle member secured along the edge of each panel adjacent the channel with one flange thereof extending laterally and fitting against the outer face of the web of the channel iron and with the other flange spaced away from the panel to provide a slot to receive the flange of the channel, pins extending through the flanges of the said rib and engaging the laterally projecting flanges of the angle members, and wedges for holding the pins with respect to the flanges of the ribs.

4. In combination in a wall mold, a channel iron having its flanges projecting outwardly from the wall to be formed and having a longitudinal rib intermediate the flanges projecting in the same direction, and having laterally extending flanges at its outer edge, a lagging panel on each side of the channel iron with its rear face flush with the rear face of the channel iron, an angle member secured along the edge of each panel adjacent the channel with one flange thereof extending laterally and fitting against the outer face of the web of the channel iron and with the other flange spaced away from the panel to provide a slot to receive the flange of the channel, and removable locking pins between the said laterally projecting flanges of the angle member and the flanges of the said rib, the said laterally projecting flanges having outwardly projecting lips adapted to hold the ends of the pins against lateral movement.

5. In combination in a wall mold, a channel having its flanges projecting outwardly from the wall to be formed and having a flanged rib extending longitudinally of the channel between the flanges, a panel having a slot along one side to receive one of the flanges of the channel, and also having a flange engaging the outer face of the web of the channel, a securing pin engaging at its inner end such last mentioned flange and at its outer end extending through the flange on the said rib, and a wedge extending 110 through the pin behind the flange on said rib.

6. In combination in a wall mold, a channel having its flanges projecting outwardly from the wall to be formed and having a flanged rib extending longitudinally of the channel between the flanges, a panel having a slot along one side to receive one of the

flanges of the channel and also having a U-shaped flange engaging the outer face of the web of the channel, a securing pin engaging at its inner end the said U-shaped flange, and at its outer end extending through the flange on the said rib, and a wedge extending through the pin behind the flange on said rib.

In testimony whereof I have hereunto signed my name in the presence of the two 10 subscribed witnesses.

CHARLES D. McARTHUR.
